UNITED STATES PATENT OFFICE.

ROBERT JOHNSTON, OF KINGSTON, PENNSYLVANIA.

REEL.

1,138,483.

Specification of Letters Patent.

Patented May 4, 1915.

Application filed January 29, 1914. Serial No. 815,130.

To all whom it may concern:

Be it known that I, ROBERT JOHNSTON, a citizen of the United States, residing at Kingston, Luzerne county, Pennsylvania, have invented new and useful Improvements in Reels, of which the following is a specification.

My invention relates to reels, and more particularly to that class of reels on which metallic tape is wound or from which it is unwound, though its use is by no means confined to this purpose. Tapes of this description are employed by surveyors, and civil and mining engineers, and are given very hard treatment. The tape is used in all kinds of weather and is often wound on the reel when wet, and the reel laid aside until again needed. Former reels inclosed the tape which, under such usage, soon rusted and became brittle and was easily broken. Furthermore, the sulfur water present in greater or less quantity in coal mines where these tapes are often used, will quickly destroy or rot the tape if it is not dried out after using.

One object of this invention is to provide a reel which will enable the tape wound thereon, to rapidly dry, the air being permitted to circulate through every part of the reel and tape to lessen the danger from rust and corrosion.

Metal tapes of two and three hundred and even five hundred feet are common, which makes a heavy load, especially after a hard day's work, and another object of the invention is to decrease the weight of the reel, though still retaining its strength and durability.

A further object is to provide a reel which may be more easily carried and leave the hands free to hold surveying instruments or other objects.

Still another object is to provide a neat, compact and attractive device of this nature, which shall be more simple and is an improvement upon former constructions, the operative parts being protected from damage.

A still further object is to prevent the coils of tape from looping, buckling or binding on the reel, with a consequent liability of breakage of the tape, when winding or unwinding.

To these and other ends, therefore, my invention includes certain novel features and

combinations of parts, all of which will be more fully disclosed hereinafter and particularly pointed out in the claims.

In the drawings, Figure 1 is a side view of one embodiment of my invention, parts being shown in dotted lines; Fig. 2 is a fragmentary perspective of the spool, to show its construction; Fig. 3 is a detail edge view, showing the pressure and guard rolls, and one of the antifriction rollers which support the spool, the latter being partly broken away to disclose its construction; and Fig. 4 is a reduced detail, showing the relation of a pressure roll to the spool.

The spool comprises a pair of annular parallel rims or treads 1, connected by a series of substantially U-shaped cross-bars or whelps 2 to form a skeleton web on which the metallic tape 3 is wound or from which it is unwound. The rims or treads 1 may be of any desired shape in cross section, and the cross-bars or whelps form a ventilated throat which permits the tape to dry out very quickly, such operation being facilitated by the interstices between the coils of tape, caused by the clips 4 (Fig. 1) on the tape, which enables the air to have access to the inner layers on the spool. The clips are marked for the graduations of the tape and are numbered to denote the distance measured.

The skeleton spool is mounted for rotation in an annular frame arranged concentrically with and encircling the spool. Said frame includes annular and parallel side plates 5, connected by brace rods 6 for strength and rigidity. Preferably, certain of said brace rods form axles for antifriction rollers 7, which may be conveniently provided with ball bearings 8 (Fig. 3). Grooved heads 9 at the opposite ends of the rollers form seats for the treads 1 constituting the ends or peripheries of the spool, which seats hold the spool in place against disengagement from the frame. The grooves also guide the spool as it is rotated in the frame, and the antifriction rollers operate as bearings for and are arranged exteriorly of the spool. A handle 10 fastened to the frame enables the operator to support the reel while he turns a second handle or knob 11 projecting from the spool to wind or unwind the tape. Preferably, I arrange three antifriction rollers 7 in triangular relation (Fig. 1) at a point about diametrically op-

posite the handle 10 to support the weight of the spool and tape, there being another roller at that side of the frame where the handle is located, but it will be understood 5 that this particular arrangement does not constitute a material part of the invention and the rollers 7 may be arranged in any other practical relation.

From the foregoing it will be seen that I 10 have provided an easily running spool or drum on which the tape may be readily wound and unwound. Owing to its inherent resiliency, the tape tends to loop, or expand like the coils of a helical spring, against 15 confinement when wound about the spool, to prevent which, and to cause the tape to lie snugly in the throat of the spool in tiers or layers, I provide tension means in the form of opposed spring-pressed pressure rolls 12 20 (Figs. 1 and 3), having their axes substantially parallel with the axis of the spool and arranged to lie in the throat of the spool. Arms or supports 13 pivoted to studs or cross braces 14 on the annular frame 25 carry pintles 15 on which said pressure rolls are journaled, the rolls being preferably tapered or frusto-conic in shape, with their bases adjacent the opposite sides of the throat of the spool. Each pressure roll ex- 30 tends inwardly from its respective side of the throat more than half way across the throat so that their reduced ends overlap to contact the tape across the entire width of the throat.

35 Tapering the pressure rolls 12 imparts a slight cant thereto, the reduced ends of the rolls being adjacent to the arms 13, so that the plane of the base of each pressure roll lies at an angle to the side of the throat, as 40 shown in detail in Fig. 4, and prevents frictional contact between the side of the throat and the base. The effective portions of the pressure rolls, that is, those portions which contact the tape, extend to the respective 45 walls of the throat to prevent the tape from working up between the bases of the pressure rolls and the adjacent walls of the throat, and binding with a consequent liability of breakage.

50 Each arm or support 13 carries a lateral rigid extension 16 in which is mounted a pin 17 arranged preferably radially relatively to the reel. Guard rolls 18 journaled on said pins 17, contact the rims or treads 1 of the spool to prevent injurious contact between the skeleton side walls of the throat of the spool and the pressure rolls 12, the guard rolls being arranged to permit the outer edges of the pressure rolls at their points of 55 contact with the tape, to lie close against the walls of the throat, as shown in Fig. 4.

56 Springs 19 preferably mounted on the studs or cross braces 14, engage the arms or supports 13 to press the rolls 12 against the coils of the tape to cause the tape to wind

snugly in the throat. The arms or supports 13 project toward each other and lie adjacent their respective rims 5. The rolls 12 lie between the arms and the opposite rims 5 with their guard rolls 18 contacting said opposite rims. The springs 19 for the respective arms 13 are coiled about the studs 14 with their inner ends engaging the said opposite rims 5 and their outer ends secured to the respective arms or supports to press the rolls 12 against the coils of tape, the arrangement of the springs being such as to also press the guard rolls 18 against their respective rims or treads 1. As the tape is wound on the spool it forces the pressure 75 and guard rolls outwardly, the guard rolls shifting axially across the rims or treads 1 and maintaining a fixed relation between the pressure rolls and the sides of the throat. Flanges 20 on the guard rolls overhang the 80 rims or treads 1 to limit the inward throw of the pressure and guard rolls, which might otherwise effect the disengagement of the guard rolls and treads, whereupon the springs 19 would force the rolls laterally 85 against the cross-bars of the skeleton throat and tend to prevent rotation of the spool. Preferably, the tape is fed from that portion of the spool diametrically opposite the handle and over one of the antifriction rollers 7. In winding the tape onto the spool, it is preferably drawn around nearly three-quarters of the circumference of the spool 90 before passing under the pressure rolls. The tape thus passes under at least three antifriction rollers which tauten the tape to cause it to conform to the circumference of the spool before being pressed into and held in place by the pressure rolls. Furthermore, the rolls under which the metallic tape passes, as it is wound upon or unwound from the spool, reduce the drag or friction which would otherwise be caused by the contact of the tape with rigid rods, diminishes the resistance of the tape against coiling, 100 and permits the tape to run easily, and there is little if any liability of the graduation clips being torn off or loosened during the winding or unwinding of the tape.

105 The bracing of the frame not only imparts strength, rigidity and durability to the reel and protects the spool and tape against injury, but together with the antifriction rollers, prevents the tape from bulging out past the frame, and kinking or breaking as 110 it is wound or unwound.

115 The annular structure of the reel enables the operator to thrust his arm through the unobstructed opening in the center to place the reel on his shoulder, thereby leaving his 120 hands free to carry other objects. The skeleton construction reduces the weight of the reel and provides for ventilation of the tape, which is thus exposed instead of being boxed in, as was formerly the case.

The arrangement and formation of the pressure rolls causes the tape to lie snugly in the throat and to wind evenly thereon without buckling. They also prevent the tape 5 from binding on the spool so that it cannot be readily unwound, the pressure rolls yielding slightly as the clips 4 pass thereunder. The operating parts of the reel are all confined within the periphery of the frame to 10 form a compact device and reduce the liability of damage thereto.

Changes may be made in the form and arrangement of the several parts without departing from the spirit and scope of the invention.

What I claim as new, is:—

1. In a reel, the combination with a spool; of a frame encircling the spool; and anti-friction rollers journaled in the frame and 20 engaged by the outer periphery of the spool, to support the spool exteriorly thereof and confine the coils of material wound on the spool.

2. In a reel, the combination of a spool 25 having treads; a frame encircling the spool; and grooved rollers journaled in and extending across the frame, the treads seated in the grooves in the rolls.

3. In a reel, the combination of a spool; a 30 frame encircling the spool; and bearings extending between the sides of the frame, and on which the spool is journaled.

4. In a reel, the combination of a spool; an annular frame concentric to and encircling the spool; anti-friction devices interposed between the spool and frame; yielding pressure rolls to engage the material wound upon or unwound from the spool; and guard rolls to contact the sides of the 40 spool, to prevent the spool from catching on the pressure rolls.

5. In a reel, the combination of a spool; a frame to support the spool; means to cause the material wound upon the spool to coil 45 snugly thereon, and hold it in place against accidental uncoiling; and guard means carried by the coil-retaining means and contacting the spool at all times to prevent injurious contact between the spool and coil-retaining means.

6. In a reel, the combination of a frame comprising a pair of plates; braces connecting said plates; rollers mounted on certain of the braces; a handle secured to the frame; 55 and a spool, the treads of which are supported by the rollers.

7. The combination in a reel, including a frame, and a spool rotatable relatively thereto; of opposed pressure rolls carried by the frame and adapted to engage the material wound on the spool; and guard rolls rigidly connected with the pressure rolls, to engage the spool and prevent injurious contact between the spool and pressure rolls.

8. The combination in a reel, including a

frame, and a spool rotatable relatively thereto; of opposed frusto conical pressure rolls carried by the frame and adapted to engage the material wound on the spool; and guard rolls rigidly connected with the pressure 70 rolls, to engage the spool and prevent injurious contact between the spool and the pressure rolls.

9. The combination in a reel, including a frame, and a spool rotatable relatively thereto; of opposed pressure rolls carried by the frame and adapted to engage the material wound on the spool, the outer ends of the respective rolls lying adjacent the opposite walls of the throat of the spool, with their inner ends extending past each other; and guard rolls rigidly connected with the pressure rolls, to engage the spool and hold the pressure rolls out of injurious contact therewith.

10. In a reel, the combination with a frame; and a spool rotatably mounted therein; of a pressure roll carried by the frame and adapted to bear upon the coils of material on the spool; and a guard roll having its 90 axis at an angle to the axis of the pressure roll and adapted to engage the side wall of the throat of the spool to prevent injurious contact of the spool and pressure roll.

11. In a reel, the combination with a 95 frame; and a spool rotatably mounted therein; of a support shiftable relatively to the spool and frame; a pressure roll carried by said support and adapted to bear upon the coils of material on the spool; and a guard roll also carried by said support and adapted to have a fixed relation to said pressure roll, said guard roll adapted to engage the spool to prevent injurious contact between the spool and the pressure roll.

12. In a reel, the combination with a 100 frame; and a spool rotatably mounted therein; of a pressure roll adapted to bear upon the coils of material on the spool; and a guard roll adapted to engage the side wall of the throat of the spool, to prevent injurious contact of the spool and pressure roll, said guard roll having a flange overlying the periphery of the spool.

13. In a reel, the combination with a 115 frame; and a spool rotatably mounted therein; of a swinging arm; a pressure roll carried by the arm and adapted to bear upon the coils of material on the spool; a guard roll carried by said arm and adapted to engage the side wall of the throat of the spool to prevent injurious contact between the pressure roll and spool; and a spring arranged to force the pressure roll against the coils of material and the guard roll against 120 the side wall.

14. In a reel, the combination with a 125 frame; and a spool encircled by and turning within the frame; of yielding pressure rolls to engage the material wound upon the 130

spool; and guard rolls to contact the sides of the spool to prevent the injurious contact of the pressure rolls and spool.

15. In a reel, the combination with an annular skeleton spool having treads at its opposite ends; of a frame comprising annular sides concentric with the treads; and grooved bearings journaled in the sides to form guides for the spool, the treads of which seat in the grooves to prevent disengagement of the spool and frame.

16. In a reel, the combination with a rotatable spool; of a pressure roll adapted to bear upon the coils of material on the spool; a guard member mounted to move with the pressure roll toward and from the material coiled on the spool; and adapted to contact the side wall of the spool; and a spring so arranged as to force the pressure roll against the coils of material, and the guard member against the side wall.

17. In a reel, the combination with a spool; of a frame encircling the spool; bearings mounted in the frame to engage and support the outer peripheries of the treads of the spool; means to cause the material to

coil closely in the throat of the spool when wound thereon; and guards for said means.

18. In a reel, the combination with a skeleton spool; of a pressure roll lying in and extending across the throat of the spool from one side wall, with its axis at an angle to the axis of the spool; and a guard carried with the pressure roll, and adapted to contact a continuous surface to prevent injurious contact between the pressure roll and the skeleton spool.

19. In a reel, the combination with a frame; and a spool; of cross bearings mounted in the frame, which extend across the throat of the spool, and rotatably support the spool in the frame, the bearings adapted to be contacted by the material as it is wound upon or unwound from the spool, to reduce the frictional drag thereof.

Signed this twenty-first day of January, 1914.

ROBERT JOHNSTON.
